(57) **CLAIM**

The ornamental design for a dustplug for a multiport optical connection device as shown and described.

DESCRIPTION

FIG. 1 is a top perspective view of a dustplug for a multiport optical connection device showing our new design;

FIG. 2 is a bottom perspective view thereof FIG. 1;

FIG. 3 is a front view thereof of FIG. 1;

FIG. 4 is a rear view thereof of FIG. 1;

FIG. 5 is a left side view thereof of FIG. 1;

FIG. 6 is a right side view thereof of FIG. 1;

FIG. 7 is a top view thereof of FIG. 1; and,

FIG. 8 is a bottom view thereof of FIG. 1.

The broken lines in the drawings depict portions of the dustplug for a multiport optical connection device that form no part of the claimed design.
